US0D1049078S

(12) **United States Design Patent** (10) **Patent No.:** **US D1,049,078 S**
(45) **Date of Patent:** **** Oct. 29, 2024**

(54) **REMOTE CONTROL**

- (71) Applicant: **Crestron Electronics, Inc.**, Rockleigh, NJ (US)
- (72) Inventors: **Daniel Previti**, Tappan, NY (US); **Gautham Basti**, Bengaluru (IN); **Howard Balch**, Bloomingdale, NJ (US); **Chetan Khanna**, New City, NY (US)

- (73) Assignee: **Crestron Electronics, Inc.**, Rockleigh, NJ (US)

(**) Term: **15 Years**

(21) Appl. No.: **29/887,669**

(22) Filed: **Mar. 23, 2023**

(51) LOC (14) Cl. **14-03**

(52) U.S. Cl.

USPC **D14/218**

(58) **Field of Classification Search**

USPC D13/218, 203.3, 217, 204-206, 174, 380, D13/388, 396, 164, 162, 168; D10/49, D10/50, 106, 104; D21/405, 456, 333, D21/566, 512-217

CPC G08C 17/02; G08C 19/00; G08C 17/00; G08C 19/28; G08C 21/04; G06F 1/16; G06F 3/0202; G06F 3/0219; G05B 19/02; G06Q 5/00; G08L 9/12; H04B 1/202; H05B 45/00; H05B 47/10; H03J 9/02; H03J 1/0025; H01H 9/235

Assistant Examiner — Samina Vieth

(74) *Attorney, Agent, or Firm* — Crestron Electronics, Inc.

CLAIM

The ornamental design for a remote control, as shown and described.

DESCRIPTION

FIG. 1 is a front perspective view of a remote control;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines in the drawings depicts portions of the remote control that form no part of the claimed design.

1 Claim, 6 Drawing Sheets
